G. U. BLASER

VEHICLE TIRE

Filed Jan. 23, 1923

FIG. 1

FIG. 2

INVENTOR
GEORGE U. BLASER
BY: Attorneys.
ATTORNEY.

UNITED STATES PATENT OFFICE.

GEORGE U. BLASER, OF CUMBERLAND, MARYLAND, ASSIGNOR TO KELLY SPRINGFIELD
TIRE COMPANY, OF CUMBERLAND, MARYLAND, A CORPORATION OF NEW JERSEY.

DESIGN FOR A VEHICLE TIRE.

Application filed January 23, 1923. Serial No. 4,969. Term of patent 14 years.

To all whom it may concern:

Be it known that I, GEORGE U. BLASER, a citizen of the United States, residing at Cumberland, in the county of Allegany, State of Maryland, have invented a new, original, and ornamental Design for a Vehicle Tire, of which the following is a specification, reference being had to the accompanying drawing, forming a part

Fig. 1 is a plan view of a portion of the article, showing the design.

Fig. 2 is a cross section through II-II of Fig. 1.

I claim:

The ornamental design for a vehicle tire as shown.

GEORGE U. BLASER.
